WILLIAM BRINK, OF HENRYETTA, OKLAHOMA.

METHOD AND APPARATUS FOR CRACKING OILS

Application filed March 3, 1925. Serial No. 12,987.

This invention relates to cracking of mineral oils and has for its object the provision of a method for the convenient recovery of gasoline from lower grade oils, as for example, a natural oil which has been passed through an ordinary type of still with consequent removal of a large portion of its gasoline content.

The principal object of the invention is the provision of a method of treatment of such oils and of apparatus for carrying out the process.

In carrying out my process I pump continuously into each of a plurality of cracking chambers the oil to be treated, subject the oil with or without the addition of field gas or casing head gasoline to heat, cause the heated mixture to pass upwardly through a relatively small pipe to be discharged against a baffle, at which point the gaseous constituents will rise and pass to the condenser, and the liquid portions will fall by gravity through an appreciable distance, from two to six feet for example, preferably four feet, to the main body of the oil, preferably in a large tank or still body wherein it may freely return to the cracking chambers.

The present process and apparatus differ from the older types of similar gasoline recovery practice in that no fire is applied to the main still, and the carbon which is removed in the still can therefore be removed from this still without caking and practically without coking, since the carbon falls into the lower hemispherical end of the still in the form of fine particles, or cinders as they are technically termed. There is a gravity flow of oil from the still into the cracking chambers and no check valve is required due to the tendency of oil to rise through a small pipe when heated and to descend in a larger pipe where there is free communication.

In the drawings, the figure illustrates diagrammatically the apparatus for carrying out my process.

10 is a pipe line communicating with the supply tank (not shown) and which may or may not have a pump, depending upon the distance and the height of the tank with relation to the cracking chambers 11. There are preferably six or more of these cracking chambers 11 spaced near the central still 12, and each communicating with the still

by means of a pipe 14, which opens into the still at a point above the junction between the straight cylindrical side 15 and the hemispherical bottom 16, thus providing an appreciable drop between the still and the cracking chamber 11.

I find it convenient to have the cracking chambers each about six feet long and somewhat over eight inches in diameter, and the still to be approximately three feet in diameter and roughly fifteen feet high. The feed pipe 10 leading into the cracking chamber 11 is reduced at its nozzle 17 to approximately one-half inch, and preferably should be centrally disposed and in line with the somewhat larger pipe 14 leading from the still to the cracking chamber. There is a fire under each cracking chamber, diagrammatically represented by the gas burner 20 and preferably all of the cracking chambers are located within a furnace 18. The heat of this fire or temperature at the cracking chamber will naturally vary with the grade of oil cracked. As an example, I use a temperature of about 800° F. with a pressure of fifty pounds per square inch in cracking an oil of the average grade of the so-called fuel oil.

Communication between each cracking chamber 11 and the primary drum 22 is by means of pipes 23 which are appreciably larger than the pipe 10, that feeds the oil to the cracking chambers. Each pipe 23 discharges against a baffle plate 25 conveniently in the form of a semi-torus, as clearly seen in the figure. The combined liquid and vapor from the cracking chambers discharging against the baffle is separated into liquid and gas, the former discharging by gravity first to the drum 22 and from there through the mouth 27 into large still 12. The level of liquid in this still is about four feet below the baffle, and in order to cause the liquid to fall through this distance rather than cling to the walls of the still I provide a short extension 28 of the pipe 29 forming the mouth 27, thus causing the liquid to drop through the center of the still and aiding in the release of entrapped gas.

The gaseous constituents of the mixture which has passed from the cracking chamber 11 to the drum 22 ascend from the drum 22 through a plurality of pipes 30 to a secondary drum 31 somewhat smaller than the primary drum 22. For the size given for

the still and cracking chambers. I find the primary drum 22 should be about twenty inches in diameter; the secondary drum 31 should be about one foot in diameter, and the third drum about six inches. From the third drum 33 the gases enter the coils 34 and are condensed in the usual manner passing finally to a gasoline receiving tank 35. The desired pressure is created in the ordinary and well-known way, by a relief valve (not shown) on the extreme lowest end of the coils, which valve opens and closes and can be set to open at any pressure desired, no pump being required in assistance unless perchance the distance from the supply tank to the cracking chambers is such as to render a pump necessary in line 10.

The cracking chambers have a comparatively long life, but should be replaced whenever the scaling becomes appreciable. The valves 40 and 41 have no other function than to close the pipes 23 and 14 respectively in case it is desired to remove or replace one of the cracking chambers.

The process in full is as follows: Oil is pumped into the cracking chamber at a steady rate equivalent with the figures given so far to about seven barrels per hour. The oil ascends through the pipes 23, discharging against the baffle 25; the liquid portion falls through a distance of about four feet to the liquid level in the still and gradually is drawn down the large still, (during which time the carbon separates and falls to the lower hemispherical portion 16, from which it may be removed through the exit 45) providing a constant flow of oil through pipe 14 from near the bottom of the tank to each of the cracking chambers.

The process is continuous and the oil passes again and again to the cracking chamber until the recovery of gasoline is complete. The gaseous portions as separated at the baffle plate 25 are not all delivered to the condensing coils. I prefer to provide the three drums in order that the heavier vapors may condense in these drums and then flow back to the still for recracking rather than to pass them to the condenser to be liquefied.

While I have described my process in great detail I do not wish to be limited to the specific figures given except in connection with the grade of oil for which these figures are applicable. In the cracking of oil there are always three elements necessary, namely, heat, agitation and pressure and all of these may vary in using different oils. The process is applicable for all sorts of different types of oil, varying from the straight crude oil of high grade to heavy gravity fuel oil and the cracking temperature will naturally vary within great limits ranging roughly from about 475° F. for an ordinary grade straight crude oil to even

more than 1,000° F. for a heavy gravity fuel oil. The pressure in the system does not vary within great limits but should be decreased as the oils are more heavy. The agitation is secured by the circulation set up by heating the cracking chambers and a very important feature is the drop through space in the large still.

In actual practice of my invention I find it convenient to have complete systems for handling the different grades of oil. I use one complete refinery as described in this specification for the better grades of oil and have other refineries in other locations where the oil is of poorer quality that is, heavier gravity. The type of oil in connection with which I have described my invention is an average grade fuel oil and I secure it from companies which pump a portion of the oil in their pipe lines and sell to me the last foot of their tank bottom settling which is too heavy to go into the pipe lines. The dimensions of the main still may be varied somewhat but I find the most satisfactory size to be as cited within general limits. I have used with success for example, more stills as small as 24 inches in diameter and others as great as 4 feet in diameter all of them varying however within the limits of 12 to 15 feet in height. The pressure varies from atmospheric to about one hundred pounds in accordance with the gravity and the kind of oil, a paraffin base oil requiring a higher pressure than an asphalt base oil, for example.

What I claim is:—

1. The method of cracking different grades of mineral oil which consists in subjecting the oil in a cracking chamber to a cracking temperature appropriate to the grade of oil ranging roughly from 475° F. for straight crude oil to in excess of 1,000° F. for heavy fuel oils, agitating the oil by passing it through a closed system, maintaining the pressure in said system of approximately fifty pounds per square inch, passing the mixture of cracked and uncracked oil to a vertically disposed baffle to separate there the gaseous portions from the liquid portions of the treated mixture, cooling and condensing the gaseous portion, returning the heavier portion of the condensed gases to the system and retaining the lighter portions of the gases as finished product, causing the liquid portion from the baffle to fall by gravity through space to the main body of the liquid, slowing the movement of a portion of the oil in the system to enable it to deposit carbon in a settling basin and withdrawing oil from said slow moving body of oil at a point appreciably above the settling basin and passing it to the cracking chamber.

2. In combination, a main still of from two to four feet in diameter and for

twelve to fifteen feet in height and having a carbon settling basin at the bottom thereof, a receiving drum mounted above and in communication with said still, a curved baffle plate in said drum, a furnace, a cracking chamber in said furnace approximately eight inches in diameter and about six feet long, a return pipe connecting said chamber with the main sill at a point appreciably 10 above said settling basin and at a height to give and op. from the still into the cracking chamber and piping from said cracking chamber for discharging the heated products from said chamber to said baffle and means 15 for collecting the gaseous products from

20

25

said baffle and for condensing same into gasoline.

3. In combination, a vertical still having a carbon settling basin at the bottom thereof, a receiving drum mounted above and in communication with said still, a baffle plate in said drum, a cracking chamber, a return pipe conveying oil to said chamber from the main still at a point appreciably above said settling basin so as to provide a gravity drop from the still into the cracking chamber, and means for conveying heated products from said chamber to said baffle.

In testimony whereof I affix my signature.

WILLIAM BRINK.
